US00D819140S

(12) **United States Design Patent** (10) Patent No.: **US D819,140 S**
 Ali et al. (45) Date of Patent: **** May 29, 2018**

(54) **ADAPTER FOR VIDEO GAME CONTROLLER**(71) Applicant: **Collective Minds Gaming Co. Ltd.**,
Maple Ridge (CA)(72) Inventors: **Darren Ali**, Maple Ridge (CA); **Ken Dornbusch**, Maple Ridge (CA)(73) Assignee: **Collective Minds Gaming Co. Ltd.**,
Maple Ridge (CA)(**) Term: **15 Years**(21) Appl. No.: **29/591,045**(22) Filed: **Jan. 16, 2017****Related U.S. Application Data**

(62) Division of application No. 29/533,367, filed on Jul. 16, 2015, now Pat. No. Des. 778,989.

(30) **Foreign Application Priority Data**

Jun. 9, 2015 (CA) 162784

Primary Examiner — Prabhakar G Deshmukh

(74) Attorney, Agent, or Firm — Bennett Jones LLP

(57) **CLAIM**

The ornamental design for an adapter for video game controller, as shown and described.

DESCRIPTION

FIG. 1 is perspective view of an adapter for video game controller showing our new design;

FIG. 2 is a front elevational view thereof; and,

FIG. 3 is a side elevational view thereof.

The broken lines illustrate unclaimed portions and form no part of the claimed design.

1 Claim, 3 Drawing Sheets
